STOVE GRID

Charles W. Agee, Chattanooga, Tenn., assignor to
Samuel Stamping & Enameling Company,
Chattanooga, Tenn., a corporation of Tennessee

Application July 14, 1952, Serial No. 20,609

Term of patent 7 years

(Cl. D81—10)

To all whom it may concern:

Be it known that I, Charles Wm. Agee, a citizen of the United States, residing at Chattanooga, in the county of Hamilton and State of Tennessee, have invented a new, original, and ornamental Design for Stove Grid, of which the following is a specification, reference being had to the accompanying drawing, forming part thereof, in which:

Fig. 1 is a top plan view of a stove grid showing my new design.

Fig. 2 is a sectional view taken on lines 2—2 of Fig. 1; and

Fig. 3 is an end elevational view of one of the

four grid loops shown in Fig. 1, and as observed from the plane of line 3—3 on Fig. 1.

I claim:

The ornamental design for a stove grid, substantially as shown.

CHARLES WM. AGEE.
